LOCKET

Michael P. Patterson, Hopkins, Minn., assignor to Great Things Incorporated, Minneapolis, Minn.

Filed Feb. 29, 1972, Ser. No. 230,547

Term of patent 14 years

Int. Cl. D11—01

U.S. Cl. D45—15

FIG. 1 is a front view of a locket embodying my new design;

FIG. 2 is a side edge view thereof as seen from the right of FIG. 1;

FIG. 3 is a bottom view; and

FIG. 4 is a sectional view taken on line 4—4 of FIG. 1. I claim:

The ornamental design for a locket, substantially as shown.
